CLAIM

The ornamental design for a double-edged knife, as
shown and described.

DESCRIPTION

FIG. 1 is a perspective view of a double-edged knife,
showing my new design;

FIG. 2 is a front elevational view, the rear being a mir-
ror image thereof;

FIG. 3 is a side elevational view, the opposite side being
a mirror image thereof;

FIG. 4 is a bottom plan view thereof; and

FIG. 5 is a top plan view thereof.

FIG. 1

FIG. 2

FIG. 3

FIG. 4

FIG. 5
